CLAIM

The ornamental design for a rack mount kit for desktop network appliances, as shown and described.

DESCRIPTION

FIG. 1 is a perspective view of a rack mount kit for desktop network appliances showing our new design thereof;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof; and,

FIG. 8 is a perspective view of the rack mount kit for desktop network appliances with environmental subject matter.

The broken lines in the drawings represent unclaimed environmental subject matter and form no part of the claim.

1 Claim, 8 Drawing Sheets
